UNITED STATES PATENT OFFICE.

CYRUS W. BALDWIN, OF CHICAGO, ILLINOIS, ASSIGNOR TO WILLIAM E. HALE, OF SAME PLACE.

GAS-ENGINE.

SPECIFICATION forming part of Letters Patent No. 276,749, dated May 1, 1883.

Application filed January 6, 1883. (No model.)

To all whom it may concern:

Be it known that I, CYRUS W. BALDWIN, of Chicago, Cook county, Illinois, have invented certain Improvements in Gas-Engines, of which the following is a specification.

My invention consists in certain improvements in gas-engines, fully described herein-after, whereby I am enabled with the use of but one cylinder to explode the mixed gases while at their greatest density, and when the crank is in the most effective position to transmit the force of the explosion.

The invention also consists of certain details of construction, fully set forth and illustrated in the annexed drawings, in which—

Figure 1 is a sectional plan of a gas-engine illustrating my invention. Fig. 2 is a sectional elevation. Fig. 3 is an end view. Figs. 4 to 10 are diagrams illustrating the working of the engine.

The cylinder A, having the usual water-jacket, is open at one end, and contains the working-piston B, the trunk-piston B', having valves v v opening inward, and the compressing-piston B². The pistons B B' are connected by the rod a, and the connecting-rod b is jointed to ears within the piston B', and at the outer end to the crank c of the main shaft C. The compression-piston B² slides on the rod a, and is attached to two rods, d d, which extend through the head of the piston B', (the openings being suitably packed,) and are connected to a cross-head, d', sliding in guide-slots x x in the sides of the trunk of the piston B', the latter being guided by a hollow cylindrical extension, A', of the cylinder A. The connecting-rod d² is jointed to the cross-head d' and to a wrist-pin, d³, on a counter-crank, d⁴, carried by the wrist-pin of the crank e, the cranks being set and pistons connected to secure the movements hereinafter described. As the connecting-rod b vibrates across the cross-head d', the said rod b is enlarged and slotted, as shown, for the passage of the cross-head d', which can slide back and forth in its guides, while the rod b vibrates across the line in which the cross-head travels.

The cylinder A has an exhaust-port, e, near the closed end, an air-inlet port, t, near the

center, a second air-port, i, near the outer end, the two air-ports communicating through a channel, f, and a gas-port, s, also near the outer end, and communicating with a gas-pipe, s'. The igniting-opening q is a short distance from the closed end of the cylinder, and channels h h, within the cylinder, extend from the rear end past the said opening. The exhaust-port is closed by a valve, e', and a valve, f', closes the channel f, each valve having a stem extending to an arm on a rock-shaft, f², vibrated from a cam, E, on the shaft C through the medium of a rod, F, and crank-arm f³.

A valve, s², in the gas-channel is connected to a stem on which bears an L-lever, G, vibrated at proper intervals by a slide-rod, G', operated by an eccentric, G², on the main shaft. The rod G' slides in an eye at the end of a lever, H, which is connected to the governor I, so that any undue increase of speed will raise or lower the rod G', and carry it from opposite the lever G, thereby preventing the lifting of the valve s², and thus cutting off the supply of gas until the speed is reduced.

The flow of gas to the igniting-opening is governed by a slide-valve, J, which is slotted to receive a flame, and carries it to the igniting-opening in the usual manner, the valve being moved by a projection, g, on the shaft C, which is carried alternately, by the shaft's revolution, against the opposite sides of a yoke 80 or frame, h, which is attached to the valve-rod h'. Quick motions are thus imparted to the valve, so as to move it suddenly and only for a short time.

In Figs. 1 and 2 the parts are in the position they occupy when the rear end of the cylinder A contains a charge of mixed gases under compression ready to explode. When the flame-carrying port in the valve J is opposite the igniting-opening q the charge will be exploded, the valve J resuming its first position at the moment of ignition, so as to prevent any outflow of gas. The pistons are moved forward under the gas-pressure, the piston B², however, at once beginning to travel away from the piston B, as shown in diagram, Fig. 4, owing to the different positions of the two cranks to which the piston-rods are con-

ected, thus compressing the air between the pistons B^2 B' . As the piston B' passes the port i and the piston B^2 passes the port t , the air flows through the channel f to the space between the pistons B^2 B , (see Fig. 4,) and as the piston B passes the port t (see Fig. 5) the compressed air is suddenly forced into the space behind the piston B , the exhaust being then opened, and traverses the said space, expelling the dead gases through the port e . The working-piston B and trunk-piston B' are now at the limit of their forward movement; but the piston B^2 continues to move in the direction of its arrow, Figs. 5 and 6, until it uncovers the gas-port s and draws in a supply of gas to mingle with the air in the space between the pistons B' B^2 . On the return movement, Fig. 7, the piston B expels the air from behind it through the exhaust-port e , the piston B^2 leaves the piston B' suddenly under the change in the positions of the cranks, and compresses the charge between it and the piston B until the parts are at the position shown in Fig. 8, when the charge will be compressed to its greatest density.

It is desirable that the charge be exploded while at its greatest compression; but it will be seen that in ordinary engines, where the charge is compressed between the working-piston and the end of the cylinder, it is impossible to explode the gases when the crank is on the dead-center. The piston is therefore withdrawn from the end of the cylinder until the crank is in the proper position, and the gas then exploded; but this relieves the charge of pressure and wastes a great part of the power used in compressing the gas. To avoid this objection the charge has been compressed in separate cylinders and then forced into the working-cylinder when the piston and crank are in proper position; but this increases the size and weight of the engine, necessitates the use of close-fitting valves, and is otherwise objectionable. By the construction shown I avoid both these objections, for after the charge is compressed to its greatest density (the parts being in the position shown in Fig. 8) the piston B , acted on by the crank b^4 , approaches the piston B^2 , Fig. 9, and the charge is transferred through the channels h to the rear of the piston without any expansion, the piston B moving forward until it is in contact with the piston B^2 , which remains nearly stationary, (see Fig. 10,) by which time the crank c is in such a position that the explosion which then follows acts most effectively to turn the shaft. The operations then follow in the order and with the effect before described. By this means I compress the charge to its greatest density and explode it without any expansion when the crank is in its most effective position, and without a second compression-cylinder or valves and packing other than those essential to every cylinder.

It will further be seen that as all the pistons are in one cylinder any leakage will re-

sult simply in a transfer of the gas from one chamber to another, so that the tight packing requisite when different cylinders are used is avoided.

It will be seen that the variable movements of the pistons are positively imparted by the double crank without any lost motion or the use of appliances liable to fail in coacting properly; but I do not limit myself to the use of such devices, as cams, eccentrics, &c., or a second crank-shaft, may be used. Other means for compressing the charge on one side of the piston and transferring it to the other after it has moved part of its stroke may be used. For instance, the charge may be transferred from one side of the piston B to the other through the piston itself.

The expulsion of the waste gases by driving a charge of air through the cylinder from end to end is an important feature, as thereby the gases are completely expelled, but without loss of time in the operation. It will be obvious, however, that this mode of expulsion may be applied when the air is admitted at one side of the cylinder and the gas expelled at the opposite side, and that the expulsion may be effected after the piston has traveled back a short distance, instead of when it is at the end of its stroke.

The movement of the igniting-valve by a tappet or any other device whereby it is caused to change its position quickly and then come to a rest is an important feature, as thereby the ignition may be effected at the precise moment required, and the opening then immediately closed.

Instead of using the pistons B^2 B' to force a charge of air through the rear of the cylinder, a separate air-cylinder may be used; or air stored under pressure in a reservoir may be employed. In this case the piston B' might be dispensed with.

I do not abandon or dedicate to the public any patentable features set forth herein and not hereinafter claimed, but reserve the right to claim the same either in a reissue of any patent that may be granted upon this application or in other applications for Letters Patent that I may make.

I therefore claim—

1. In a gas-engine, the combination of a working-cylinder, two pistons, and appliances, substantially as described, for operating them independently, and air and gas ports and channels, substantially as set forth, whereby the charge of explosive gases is compressed in front of the working-piston and then transferred to the rear thereof and exploded, substantially as specified.

2. The combination of the cylinder, its pistons B B^2 , air and gas ports and channels, and appliances, substantially as described, whereby the piston B is moved from the rear of the cylinder to the piston B^2 , and the gases thereby forced from the front to the rear of the piston B , and the pistons then separated while

both traveling forward to receive between them a second charge of gases, substantially as set forth.

3. The combination of the cylinder, pistons

5 B B², and ports, passages, and valves, and operating devices, substantially as described, whereby the two pistons are separated while traveling forward to receive a charge of gases between them, and are then brought toward 10 each other while traveling back to compress said charge until the piston B reaches the limit of its motion, and said piston is then brought against the piston B² to force the charge to the opposite side of the piston B, 15 substantially as set forth.

4. The combination, with the cylinder A and its ports and passages, and with the piston B, rod *a*, connecting-rod *b*, and shaft C and crank *c*, of the piston B², rods *d*, connecting-rod *d'*, 20 and supplemental crank *d''*, substantially as set forth.

5. The combination of the cylinder, its ports, and valves and pistons B B', connected together, and intermediate and independently- 25 operating piston, B², substantially as set forth.

6. The combination of the cylinder, piston B, piston B', connected thereto and provided with a trunk, and piston B², connected to rods extending through the piston B', and attached 30 to a cross-head sliding in guides of the trunk, substantially as set forth.

7. The combination, with a gas-engine, of ports arranged at opposite portions of the working-cylinder, and air-passages and valves, 35 substantially as set forth, whereby a charge of air is carried through the cylinder away from

the piston, when the latter is at the limit of its forward motion, after the explosion of the gases and prior to the admission of a new charge, substantially as set forth.

8. The combination, with the working cylinder and piston of a gas-engine, of exhaust and air ports and passages arranged to admit a charge of air after the explosion and then to permit the same to be expelled by the backward movement of the piston, as set forth.

9. The combination of the cylinder, connected pistons B B', intermediate piston, B², and ports and passages arranged to carry the air from between the pistons B² B' to the rear of 50 the piston B, substantially as set forth.

10. The combination of the cylinder A, having the exhaust-port *e*, communicating air-ports *t* *i*, igniting-opening *q*, and gas-port *s*, arranged and provided with valves, substantially as set 55 forth, and working-piston B, piston B', provided with air-openings and valves, and intermediate piston, B², substantially as set forth.

11. The combination of the gas-inlet valve and operating appliances, a reciprocating rod, 60 G', constituting part of said operating appliances, and a governor and connections whereby said rod is thrown out of connection with the other parts when the speed of the engine becomes excessive, substantially as set forth. 65

In testimony whereof I have signed my name to this specification in the presence of two subscribing witnesses.
